Furniture Factories, Lenoir, N.C., a partnership

Filed Oct. 12, 1962, Ser. No. 72,093

Term of patent 14 years

(Cl. D33—1)

FIGURE 1 is a front elevational view of a furniture panel or similar article, showing my design wherein the ornamentation is applied to a wide embodiment;

FIGURE 2 is a front elevational view of the panel of FIGURE 1 wherein the ornamentation is applied to a more narrow embodiment; and

FIGURE 3 is a side elevational view of the panel shown in FIGURE 1 and is substantially similar to the side elevational view of the panel shown in FIGURE 2.

The back of both embodiments of the furniture panel or similar article is conventionally plain.

I claim:

The ornamental design for a furniture panel or similar article, as shown and described.
